APPARATUS FOR APPLYING AND REMOVING MAKE-UP

Antoine Francois Peyron, 4 Rue de Londres,
Paris, France

Filed May 25, 1959, Ser. No. 56,038

Term of patent 14 years

(Cl. D86—10)

Fig. 1 is a front view of an apparatus for applying and removing make-up showing my new design.

Fig. 2 is a side view of the same.

Fig. 3 is a lower end view of the same.

The dominant features of my design reside in full lines.

I claim:

The ornamental design for an apparatus for applying and removing make-up, as shown and described.
